UNITED STATES PATENT OFFICE

JOSEPH L. WILLFORD, OF MINNEAPOLIS, MINNESOTA, ASSIGNOR OF ONE-HALF HIS RIGHT TO EPHRIAM RUSSELL, OF SAME PLACE.

IMPROVEMENT IN MIDDLINGS-PURIFIERS.

Specification forming part of Letters Patent No. 171,542, dated December 28, 1875; application filed October 8, 1875.

To all whom it may concern:

Be it known that I, JOSEPH L. WILLFORD, of Minneapolis, in the county of Hennepin and State of Minnesota, have invented certain new and useful Improvements in Middlings-Purifiers, which improvements are fully set forth the following specification, reference being had to the accompanying drawings, in which—

Figure is a vertical longitudinal section of the machine; Fig. 2, a vertical cross-section; Fig. 3, a front view of the hopper and series of inclined overlapping shelves; Fig. 4, a top or plan view of the machine, with the cover removed, showing the valves and devices for operating them.

My invention relates to improvements in devices for separating the different elements of which flour-middlings are composed; and the invention consists in devices arranged over the shaker for regulating the air-currents through the different portions thereof; also, in the combination and arrangement of devices for operating the shaker and inclined overlapping shelves, over which the material passes from the hopper to the head of the shaker; also, in the arrangement of devices for giving a transverse reciprocating motion to the bottom of the hopper; and, finally, in the combination, with transverse conveyers, of an adjustable cut-off between them, all as hereinafter fully described.

A, in the drawings, is the receiving-hopper, provided with an adjustable strip, *a*, for regulating the feed. B is the movable bottom of the hopper, and which receives a transverse reciprocating motion through the medium of the reciprocating shaker D, angular pivoted lever *b*, and connecting-rod *b'*, to which one end of the movable bottom is secured.

The above-described motion to the bottom B causes the material to seek its level in the hopper, whether there is much or little therein, and feed it evenly under all circumstances.

C are a series of reciprocating inclined overlapping shelves, secured to the shaker-frame between the bottom of the hopper and the head of the shaker, over which the middlings from the hopper pass, and while passing from one shelf to another are subjected to air-cur-

rents produced from or by the suction-fan F, which separate and carry off the light fuzzy particles of the material which clogs the meshes of the bolt-cloth, thereby obviating the use of devices for keeping the bolting-cloth clear, for whatever light material reaches the shaker falls upon a blank section of board bottom, where the reciprocating motion of the shaker causes the lighter particles to come to the top of the material, and as they reach the bolting-cloth are in a favorable position to be drawn away by the ascending air-currents through the cloth. Just in rear of the series of overlapping shelves above described is a pivoted valve, *g*, for regulating the inlet of air between them, and which is operated by a lever, *g'*, on the outside of the machine for adjusting the same.

D is the shaker, covered with bolting-cloth in the usual manner, and is suspended by swinging arms *d*, pivoted from arms *d'* secured in slotted brackets *d''* on the frame of the machine, (see Fig. 5,) so that the arms *d'* can be readily adjusted in the slots *d''* of the brackets, and, when adjusted, are held by the screw-bolt and nut *d'*. The object of suspending the shaker as above described is, that when adjusting the hangers so as to throw the point of support to or from a perpendicular, for increasing or decreasing the flow or speed of the material over the cloth, the shaker does not need supporting by hand. The shaker is reciprocated by means of the eccentrics *e* on the fan-shaft *c'* and pitman *c''* connecting with the rods *c'''*, which connect the hangers with the front end of the shaker, as clearly shown in Fig. 3.

Former devices for the purpose of regulating the draft or passage of air to the exhaust-fan have generally consisted of horizontal slides or obstructions, and usually divided the air into a few currents, which of course causes greater draft at certain points through the cloth than others, and besides the heavier particles drawn away settle down on top of these slides or valves, which necessitate frequent removal by hand.

By my devices, as hereinafter described, the air can be evenly distributed through all parts of the machine.

In the drawings, E and E' show the position of the valves, which are made in two sections for giving a stronger draft through one end of the shaker than the other, if desired, section E being open and section E' closed. The blank e' in section E allows the heavier particles which have been drawn away to settle beneath the fan, and by accumulating they open the valve f, and pass off with the waste from the shaker D, through the valve k on the rear of the machine.

Fig. 4 shows the manner of opening and closing the valves. h and h' are two levers pivoted to the sides of the machine at i, Fig. 1, for operating the valves of the two sections E and E'. When the valves are to be opened or closed it is only necessary to draw out or push in the levers, which are held in position by the wedges j, as clearly shown in Fig. 4. The valves e are attached to the frame G by wire staples, and the frame is set at an angle or inclined toward the tail of the shaker, so that the air-currents in passing through sweep directly across the valves, and thereby keep them clear. The blank e' also permits a too strong and direct draft over the tail of the shaker, and admits of the fan being placed low down or near the cloth. I are longitudinal openings through the sides of the machine, just below the shaker, for the admission of air.

Usually there are two or more grades of bolting-cloth on the shaker, the finest at the head thereof, and all that passes through it is finished, and that which passes through the coarse cloth is called "returns," and is kept separate, to be reground and rebolted or purified. Sometimes only one grade of cloth is used with the same general results; but the point on the cloth where the division should be made varies with the quality of the material, or in grinding high or low, as the case may be. An adjustable device is therefore necessary in order to divide at will the material passing through the shaker at any point thereon, and kept from mixing while falling into the hoppers, which is accomplished as follows: J J are gather-boards, which collect the material and deliver it to the two trans-

verse conveyers L L. M is an adjustable cut-off between them. Said cut-off is made in two parts, m m', sliding together and gilded, as shown in Fig. 5. The part m' reaches up to the cloth on the shaker, and rests upon the sides of the machine formed by the openings I, and as it is swung to or from the center it is self-adjusting in length, and can therefore be set at any desired point to divide the middlings passing through the bolting-cloth.

Motion is communicated to the fan-shaft by a belt from pulley N to the power-wheel, which in turn communicates motion to the conveyers through the medium of band-pulleys O O', belt O², and gear-wheels P P'.

Further description of the operation of the machine is deemed unnecessary, it being obvious from the foregoing description.

I claim as my invention—

1. The combination, with the shaker D and suction-fan F; of the valves e, in two sections, E E', operated as described, and arranged at an angle, or inclined toward the tail of the shaker, substantially as and for the purpose specified.

2. The combination, with the shaker D and inclined overlapping shelves C, of the operating mechanism, consisting of the pivoted hangers d, rods d¹, slotted brackets d², rods e¹, pitmen e², and eccentrics e³ on fan-shaft, all being arranged to operate in the manner substantially as shown and described.

3. The combination, with shaker D and overlapping shelves C, of the transverse reciprocating bottom B of the hopper, operated through the medium of the shaker D, angular lever b, and connecting-rod b', substantially as described.

4. The combination, with the transverse conveyers L L and shaker D, of the adjustable cut-off M, formed in two parts, m m', sliding together in the manner substantially as and for the purpose specified.

In testimony that I claim the foregoing I have hereunto set my hand.

JOSEPH L. WILLFORD.
